UNITED STATES PATENT OFFICE.

FRANCIS CREE, SR., OF DENTON, ENGLAND.

APPARATUS FOR WINDING THREAD.

SPECIFICATION forming part of Letters Patent No. 674,114, dated May 14, 1901.

Application filed November 14, 1899. Serial No. 736,987. (No model.)

To all whom it may concern:

Be it known that I, FRANCIS CREE, Sr., a subject of the Queen of Great Britain, residing at Denton, in the county of Lancaster, England, 5 have invented new and useful Improvements in Apparatus for Winding Thread, of which the following is a specification.

This invention relates to an improved apparatus for winding sewing-thread in the form of 10 a long cylindrical cop with conical ends suitable for use in lock-stitch sewing-machines which are provided with revolving carriers for the under or "lock" thread.

The nature of my said invention and the 15 manner in which the same is to be performed or carried into practical effect will be readily understood on reference to the sheet of drawings hereunto annexed and the following explanation thereof.

20 Figure 1 of the drawings is a side view of one of my cops, showing the crossed coils of the conical layers. Fig. 2 is an end view of the nose of the cop. Fig. 1^a is a longitudinal section of a long cylindrical cop of sewing-thread 25 with conical ends wound in accordance with my invention, and Fig. 2^a is a similar view showing the same bent or curved into a circular form to fit into the revolving carrier of the lock-stitch sewing-machine. Fig. 3 is a 30 side elevation of my improved apparatus for winding such cops of sewing-thread. Fig. 4 is a plan view of the same; and Figs. 5 and 6 are detached views, hereinafter more particularly referred to.

35 The object of the invention is to wind the thread in the form of a long cylindrical cop built up of a series of cones superposed so that one end *a* of the cop forms an obtuse cone and the other end *b* a reversed 40 or hollow cone. The thread from the hollow or "butt" end *b* is drawn through the hollow center of the cop and is delivered at the "nose" end *a*. As the thread is drawn off the cop remains of the same diameter and 45 solidity to the end, but diminishes gradually in length from the rear end *b* as it is drawn off. Another great advantage derived from this method of winding the thread is that it enables a cop containing a very considerable 50 length of sewing-thread—say from one thousand to fifteen hundred yards—to be used as the under or lock thread of a sewing-machine

in a continuously-revolving carrier without any tendency to cause the thread to "snarl" or "kink" by overtwisting.

55 The improved machine consists principally of a head-stock *c*, (see Figs. 3 and 4,) carrying a revolving spindle-holder *d*, in combination with a reciprocating thread-guide *e*, mounted on a carriage *f*, sliding horizontally 60 upon a bed-plate *g* and actuated by means of a slowly-revolving screw *h*. The spindle-holder *d* is fitted with a small grooved pulley *i*, driven rapidly by an endless band from a larger pulley, which is actuated by foot, hand, 65 or other power. The spindle *k* is tapered, and its butt-end fits tightly in the holder *d*, its extreme end being steadied by a spring-support *l*. This end is fitted with a loose cone *m*, between which and the thinner end 70 of the spindle *k* the end of the thread to be wound is held tight. The butt-end of the spindle *k* is also provided with a cone *n*.

75 The bed-plate *g* extends longitudinally below the spindle *k*, and the carriage *f*, which slides along the bed-plate *g*, supports the thread-guide *e*, which is in the form of a lever moving rapidly to and fro in a horizontal direction over the spindle *k*. This thread-guide *e* is moved horizontally in one direction 80 by means of a rocking bar *o*, acting against a finger *p*, and in the reverse direction by means of a coiled spring *q*. The rocking bar *o* is actuated by a lever *r*, (see also end view, Fig. 6,) which is held by the spring *q* against a 85 double cam or former *s*, driven by an endless band *t* from the head-stock spindle-carrier *d*.

85 The screw *h* for traversing the thread-guide carriage *f* is caused to make a portion of a revolution intermittently by means of a jointed grip-motion *u*, (see also end view, Fig. 5,) connected to a lever *v*, actuated by an eccentric or cam *w*, mounted on the spindle-carrier *d*, and as the cam *w* revolves the lever *v* will be raised to cause the cam-lever *u* through 90 the link *u'* to grip the feed-wheel *u²* and give it a partial turn. The working surface of this eccentric or cam *w* is made conical, as shown at *x*, Fig. 4, so that by shifting it endwise on its spindle *d* by means of the regulating-screw *y* the feed of the carriage may be 95 varied.

100 The half-nut *z*, (see Fig. 3,) which works on the screw *h*, is hinged to the carriage *f*,

so that it can be lifted out of gear with the screw *h* when it is desired to move the carriage by hand to the extreme right, so as to commence winding a fresh cop. It will be evident that the slowly progressive motion of the thread-guide carriage, combined with the rapid to-and-fro motion of the thread-guide, will cause the thread to be wound on the spindle in spiral coils crossing each other and forming a series of superposed cones from end to end in the form shown.

The revolutions of the spindle *k* should not be exactly equal to or an exact multiple of the reciprocations of the thread-guide *e*. In the machine shown in the drawings the spindle will make something over a revolution and a half for each complete back-and-forth movement of the guide *e*, and in consequence the thread will be laid in spiral coils extending from the base to the tip of the cone and back again, Figs. 1^a and 2^a, to form superposed conical layers with the successive spiral coils crossing and binding each other in place. As this crossed spiral coiling is moved progressively forward from the conical butt toward the tip of the spindle a long cylindrical cop is formed with a hollow conical base and with the threads so bound together that the cop can be bent around into a curved form without breaking and the thread can be drawn off from the interior without catching or kinking.

The method of winding and its product—the finished cop herein disclosed—form the subject of a separate application filed by me July 15, 1899, Serial No. 723,994.

I claim as my invention—

1. The improved apparatus herein described for winding thread into long hollow cylindrical cops, and comprising the combination of a winding-spindle having a tapered butt and means for revolving the spindle with a thread-guide and means for reciprocating the latter in relation to the revolutions of the spindle to lay the thread in spiral coils crossing each other and feed mechanism to advance the guide in relation to the length of the spindle.

2. A machine for winding sewing-thread in the form of a long hollow cylindrical “cop” having a conical nose and a hollow conical base for use in a lock-stitch sewing-machine, comprising the following elements in combination, a sliding carriage, a spindle provided with means for causing its rapid revolution, and with a conical butt-end, a finely-threaded screw parallel with the said spindle and provided with means for slowly revolving the same, a half-nut made with a fine thread gearing with such screw and carried by said sliding carriage that when placed in gear with the screw it will impart a slowly progressive endwise motion of the carriage from butt to point of the said spindle, and when thrown out of gear it will allow the said carriage to be moved back to the “butt-end” of the spindle to commence a fresh “cop” and a rapidly-reciprocating thread-guide mounted upon the said sliding carriage, all substantially as described.

In testimony whereof I have signed my name to this specification in the presence of two subscribing witnesses.

FRANCIS CREE, SENIOR.
